COSMETIC APPLICATOR

Albert R. Ruthsatz, Chicago, Ill., assignor to The Schell Mfg. Co., Inc., Chicago, Ill., a corporation of New York

Application July 3, 1944; Serial No. 543,354

13 Claims. (Cl. 15—230)

1

This invention relates to improvements in a cosmetic applicator, and more particularly to a device for applying a cosmetic substance or compound to the human body.

In the past, difficulty has been experienced in the application of various cosmetics to portions of the human body. This has been found to be especially true in connection with the application of liquid cosmetics, such as that used upon the legs in lieu of stockings. Such make-up material was frequently applied by hand, and such operation of course soils the hands of the user and frequently results in an uneven application of the make-up liquid, resulting in an unsightly appearance.

With the foregoing in mind, it is an important object of the instant invention to provide a make-up or cosmetic applicator with which a cosmetic may be applied to the human body readily and easily, and without soiling the hands or nails of the user.

Another object of the invention resides in the provision of a cosmetic applicator designed to apply cosmetic, and especially a liquid cosmetic, to the human body evenly and smoothly without unsightly lines or marks, and without any need of the user's hands ever coming in contact with the cosmetic.

A further object of the instant invention resides in the provision of a liquid cosmetic applicator in the form of a roll having an absorbent surface pad thereon, there being means for engagement by the hand of the user to manipulate the roll, the applicator being highly desirable for even and expeditious application of liquid leg make-up.

It is also an object of this invention to provide a cosmetic applicator highly desirable for use in the application of a liquid cosmetic to the human body, which applicator includes a roll having an absorbent surface pad thereon, which pad is so designed so as to provide spaced regions of greater absorptive capacity than the remainder of the pad, thus insuring an easy pick-up of the liquid by the applicator and the carrying of a sufficient amount of liquid by the applicator to avoid streaking.

Still another object of the instant invention is the provision of a liquid cosmetic applicator which is extremely simple to use, economical both in use and manufacture, and which requires little, if any practice to properly manipulate.

While some of the more salient features, characteristics and advantages of the instant invention have been above pointed out, others will become apparent from the following disclosures,

2

taken in conjunction with the accompanying drawing, in which:

Figure 1 is a fragmentary diagrammatic view illustrating the use of an applicator embodying principles of the instant invention;

Figure 2 is a view in elevation of the applicator itself;

Figure 3 is an enlarged fragmentary vertical sectional view through the applicator of Figure 2, with parts shown in elevation;

Figure 4 is a fragmentary inside face view of a fabricated strip of stock prior to the winding of the stock upon the applicator roller;

Figure 5 is a fragmentary transverse sectional view through the applicator, illustrating the stock strip of Figure 4 partially wound upon the applicator, for purposes of clarity; and

Figure 6 is a fragmentary vertical sectional view of the same character as Figure 3, but showing a slightly different construction of absorbent surface pads for the applicator.

As shown on the drawings:

In Figure 1 the illustrated embodiment of the instant invention is shown in use in the application of liquid make-up to a leg. It will be appreciated, however, that the applicator might equally as well be used for the application of sun-tan make-up, or the equivalent to the arms, shoulders, or other portions of the human body, and may at times be used for the application to the body of a medical substance for healing or soothing purposes. The application of such a medical substance with the instant invention is both gentle and thorough.

With reference now more particularly to Figures 2 and 3, it will be seen that the applicator embodies a yoke-shaped frame 1, provided with any suitable means for engagement by the hand of a user, such, for example, as the illustrated handle 2. The handle, if so desired, may be integral with the yoke frame 1, and these parts may be made of any suitable material, an attractively colored plastic being quite satisfactory. Between the legs of the frame 1, a roller 3 is disposed, and this roller may be of wood, plastic, or any other suitable material. The roller is preferably solid as illustrated, and provided centrally at each end with a pin 4 which may be fixedly secured in the roller. The pin 4 projects sufficiently far beyond the ends of the roller to function as a journal, this portion of the pin seating within a suitable opening 5 in the adjacent leg of the frame so that the pin may freely rotate therein.

The roller 3 is provided with an absorbent surface pad, generally indicated by numeral 6. In

that embodiment of the invention illustrated in Figures 3, 4 and 5, this surface pad is made up from an elongated fabricated strip of absorbent fabric wound spirally around the roller. The winding of the fabric is preferably done under sufficient tension to make a tight winding so that when the applicator is used against the body, there will not be any bulging or creasing of the surface pad.

The fabric going to make up the pad is illustrated in Figure 4 and comprises an elongated strip of suitable material, such as gauze of the type used for gauze bandages. The main strip portion is initially wider than the roller 3 and side marginal portions of this main strip are turned inwardly against the intermediate portion of the strip as indicated at 7 and 8 in Figure 4. Between the inturned marginal portions 7 and 8 another and initially separate strip 9 of similar material is attached to the main strip. The strip 9 is relatively narrow, so that it does not completely fill space between the edges of the inturned marginal portions and is preferably centrally located between those edges, so that there will be a pair of spaced channels running longitudinally of the strip, indicated by numerals 10 and 11, in which channels the subsequent fabricated strip is only of single-ply, while elsewhere it is double-ply.

The fabricated strip, so constructed, is then wound spirally upon the naked roller 3, as indicated in Figure 5. When the desired thickness of pad has been acquired, the free end of the strip may be anchored to the portion already on the roller in any suitable manner, such as a satisfactory adhesive of such character as not to be disrupted when the applicator is supplied with liquid make-up. When the fabricated strip has been wound around the roller to form the surface pad 6, there will be spaced regions or areas of greater absorptive power than the remainder of the pad, such regions or areas being provided by the channels 10 and 11 whereat the fabric is only of single-ply. The single-ply portions will be held apart by the inturned marginal portions 7 or 8 on either side thereof, as clearly seen in Figure 3. Thus, the region embodying the single ply arrangement will be more absorptive than the rest of the pad, and thus the pad may hold a goodly quantity of liquid cosmetic and insure an even and smooth application of that cosmetic to the body with relatively light pressure.

It will be appreciated that the regions of greater absorptive power may be provided in some other satisfactory manner, and it may be that only one such region is required. In other instances, several regions scattered over the surface pad without any particular symmetrical arrangement may be desired.

In Figure 6 I have illustrated another form of surface pad generally indicated by numeral 12. In this instance, this pad includes merely a single thickness strip of fabric wound spirally upon the roller 3 into a number of layers 13. This pad may likewise be satisfactorily made of gauze of the type of gauze bandage, and in this instance there are no multi-thickness portions, a strip of the material merely being wound around the roller until a pad of the desired thickness is reached. Such an applicator will not have any regions of greater absorptive power than any other part of the pad, but the pad will be equally absorptive throughout.

In use, the applicator is quite efficient and very simply handled. With reference to Figure 1, it will be seen that the user need only grasp the handle 2 in her hand 14. The liquid cosmetic is preferably placed in an open vessel, and the roller with its surface pad is dipped into the cosmetic. Then the applicator is rolled along the leg 15 of the user with an upward stroke leaving behind it an even smooth stripe of make-up as indicated by numeral 16. In this manner, the leg may be smoothly and evenly covered with make-up entirely therearound. It will be especially noted that the user's hand never contacts the make-up, the finger-nails are not soiled, and the application of the make-up is done very expeditiously with a minimum of effort.

It will further be appreciated that the applicator is economical in construction, highly economical in use, in that it results in less wastage of make-up than most frequently occurred heretofore, and the applicator may be repeatedly used, having a long life.

It will, of course, be understood that various details of construction may be varied through a wide range without departing from the principles of this invention, and it is therefore not the purpose to limit the patent granted hereon otherwise than necessitated by the scope of the appended claims.

I claim as my invention:

1. A make-up applicator for applying a liquid cosmetic to the human body, including a roller, hand holding means associated with said roller, and an elongated strip of absorbent fabric wound around said roller to provide an absorbent pad of multiple plies, said fabric strip being of plural plies over its major portion with a relatively narrow portion of fewer plies than present in said major portion extending circumferentially of the roller in an intermediate portion thereof.

2. A make-up applicator for applying a liquid cosmetic to the human body, including a roller, hand holding means associated with said roller, and an elongated strip of fabric wound around said roller, said strip being fabricated to provide a relatively narrow path around said roller of less plies than the remainder of the wound strip.

3. A make-up application for applying a liquid cosmetic to the human body, including a roller, hand holding means associated with said roller, and an elongated strip of gauze wound around said roller to provide a multi-ply surface pad, said strip including a sheet of gauze having the side margins turned inwardly over the central portion, and a second strip of gauze of less width than the space between the inturned side edges disposed substantially evenly between said edges on the main strip leaving a relatively narrow single-ply channel on each side of said second strip.

ALBERT R. RUTHSATZ.
